UNITED STATES PATENT OFFICE.

WILLIAM H. BROWN, OF CLEVELAND, OHIO.

DESIGN FOR A SPRING-OILER.

53,406.

Specification for Design.

Patented June 10, 1919.

Application filed December 6, 1916. Serial No. 135,493. Term of patent 3½ years.

To all whom it may concern:

Be it known that I, WILLIAM H. BROWN, a citizen of the United States, residing at Cleveland, in the county of Cuyahoga and State of Ohio, have invented a new, original, and ornamental Design for Spring-Oilers, of which the following is a specification, reference being had to the accompanying drawing, forming part thereof.

The three figures shown in the drawing annexed are, respectively, a perspective view, a side elevation, and an edge elevation of my design.

I claim:

The ornamental design for a spring oiler as shown.

WILLIAM H. BROWN.
